UNITED STATES PATENT OFFICE.

JOHN D. TAYLOR, OF WILKINSBURG, PENNSYLVANIA; MARY E. TAYLOR, EXECUTRIX OF SAID JOHN D. TAYLOR, DECEASED, ASSIGNEE TO THE UNION SWITCH & SIGNAL COMPANY, OF SWISSVALE, PENNSYLVANIA, A CORPORATION OF PENNSYLVANIA.

RAILWAY SIGNALING.

1,144,509.

Specification of Letters Patent. Patented June 29, 1915.

Application filed November 18, 1913. Serial No. 801,617.

To all whom it may concern:

Be it known that I, JOHN D. TAYLOR, a citizen of the United States, residing at Wilkinsburg, in the county of Allegheny and State of Pennsylvania, have invented certain new and useful Improvements in Railway Signaling, of which the following is a specification.

My invention relates to railway signaling, and particularly to signaling for stretches of single track over which traffic moves in both directions, such for example, as stretches of single track between passing sidings.

I will describe two forms of signaling system embodying my invention, and will then point out the novel features thereof in claims.

In the accompanying drawings, Figure 1 is a diagrammatic view showing a stretch of single track having applied thereto one form of signaling system embodying my invention, the signals being automatically controlled as to the direction of traffic by cars or trains approaching the stretch. Fig. 2 is a view similar to Fig. 1 but showing a modification in which the signals are controlled as to direction of traffic by manually operable means.

Similar reference characters refer to similar parts in both of the views.

Referring first to Fig. 1, A—B is a stretch of single track between two passing sidings E and F, over which stretch traffic moves in both directions. Traffic through this stretch from east to west is governed by signals S', S² and S³ located at intervals through the stretch, and traffic through the stretch from west to east is governed by other signals S², S⁴ and S⁵, located also at intervals through the stretch. The stretch is divided into a plurality of sections A—C, C—D and D—B, and as here shown a pair of opposing signals is located near each junction of adjacent sections, but I do not wish to limit myself to this particular location of the signals.

Each section A—C, etc., is provided with a track circuit comprising as usual the rails of the section, a track battery b, and a track relay T. Extending in each direction from

the ends of the stretch A—B, is a preliminary section A—G or B—H, each of which is also provided with a track circuit similar to that for each of the sections of the main stretch.

For each signal I provide a signal relay for the control thereof; in the drawing, each signal relay is designated by the reference character R with an exponent corresponding to the exponent of the signal which it controls. For example, signal S' is controlled by relay R', signal S² by relay R², etc. The circuit for signal S' is from battery 1 through wire 2, contact 3 of relay R', wire 4, signal S', wire 5 to battery 1. The circuit for each of the other signals is similar.

In order to control the signals as to the direction of traffic through the stretch A—B, I provide two signal relay circuits, one of which includes the signal relays for the signals governing traffic in one direction, and the other of which includes the signal relays for the signals governing traffic in the other direction; and I provide means for energizing one or the other of these signal relay circuits at a time, and for insuring that when either circuit is energized the other is deenergized. As here shown, the several signal relays are connected in multiple in their circuits, and the branch for each relay is controlled by one of the track relays. Thus the signal relays R⁵, R³ and R' for the westbound signals are bridged in multiple across a line wire 6 and a common wire 7, and the signal relay circuit thus formed is at times supplied with current from a battery 9 at one end of the stretch, as hereinafter explained; and the signal relays R², R⁴ and R⁶ for the eastbound signals are bridged in multiple across a line wire 8 and the common wire 7, and the signal relay circuit thus formed is at times supplied with current from a battery 10, as hereinafter explained. The branch of the westbound signal relay circuit including relay R⁵ is from line wire 6 through wire 11, contact 12 of track relay T', wire 13, signal relay R⁵, wire 14 to common wire 7. The branches for relays R² and R' are similar to that for relay R⁵, except that the

branch for relay R' includes contacts 15^a of a polarized relay K for a purpose herein-after explained. The branch of the east-bound signal relay circuit which includes relay R^s is from wire 8 through wire 16, contact 17 of track relay T^s , wire 18, relay R^s , wire 19 to common wire 7. The branches for relays R^4 and R^5 are similar to that for relay R^s , except that the branch for relay R^s includes contacts 15^a of a polarized relay K' for a purpose hereinafter explained. It will be seen, therefore, that the branch for each signal relay is controlled by the track relay for the section through which the corresponding signal governs traffic, so that when a section is occupied by a car or train, the circuits for both signals governing traffic through that section are always open and the signals therefore indicate "danger."

The means which I have herein shown for controlling the supply of current to the signal relay circuits comprises the two polarized relays K and K' , each of which includes a winding and a polarized armature 15. Relay K controls the circuit for signal relays R^2 , R^4 and R^s , and relay K' controls the circuit for signal relays R' , R^3 and R^5 . When armature 15 of relay K' is in the position shown, the upper terminal of battery 9 is connected with line wire 6, the connection being through wire 20 and contacts 15^a; the lower terminal of battery 10 is constantly connected with common wire 7, hence with armature 15 in this position, relays R' , R^3 and R^5 are energized. Obviously, when contact 15 swings to its other position the connection to wire 6 will be opened and signal relays R' , R^3 and R^5 will be deenergized.

The circuit for signal relays R^2 , R^4 and R^s is similarly controlled by polarized relay K .

The windings of the polarized relays K and K' are included in series in a circuit which is controlled by each of the track relays T' , T^s and T^s of the stretch A—B, and means are provided for passing current through this circuit in one direction or the other. This circuit is traced hereinafter. The polarized relays are so connected in this circuit that when current flows in one direction through the circuit, relay K' is energized in such direction as to close the westbound signal relay circuit and relay K is energized in such direction as to hold the eastbound signal relay circuit open; and conversely when current flows in the other direction, relay K is energized in such direction as to close the eastbound signal relay circuit and relay K' is energized in such direction as to hold the westbound signal relay circuit open.

The means shown in Fig. 1 for controlling the polarized relays K and K' comprises the track relays T and T' of the pre-

liminary sections. When one of these track relays is opened, current is caused to flow through the windings of the polarized relays in one direction, and when the other track relay is opened, current is caused to flow through the circuit in the other direction. A detailed explanation of this portion of the system will appear in the following explanation of the operation of the system.

The operation of the system shown in Fig. 1 is as follows: With the polarized relays K and K' in the positions shown in the drawing, the westbound signals are clear and the eastbound signals are at danger. I will assume first that a westbound train approaches the stretch A—B. As this train enters preliminary section B—H, the opening of track relay T^s causes polarized relays K and K' to be energized through the following circuit—from battery 9, through wire 21, contact 22 of track relay T , wire 23, winding of polarized relay K' , wire 23, contact 24 of track relay T' , wire 25, contact 26 of track relay T^s , wire 27, contact 28 of track relay T^s , wire 29, winding of polarized relay K , wire 30, contact 31 of track relay T^s , wire 32 and common wire 7 to battery 9. The direction of the current in this circuit is such that the armatures 15 and 15^a of the polarized relays remain in the positions in which they are shown in the drawing, hence the presence of the train in the preliminary section B—H causes no change in the signals. As the train enters section B—D, it opens track relay T^s , thereby opening at contact 43 the branch circuit including signal relay R' , so that signal S' then changes to danger indication. The opening of track relay T^s also opens the circuit including the windings of the polarized relays K and K' , and this circuit continues to be opened by one track relay or another as long as the train occupies any part of the stretch A—B; consequently, as long as the train is in any part of the stretch, the polarized relays cannot be energized and therefore the eastbound signals S^2 , S^4 and S^s cannot be cleared and the westbound signals S' , S^3 and S^5 cannot be taken away from the westbound train. In other words, after a train has entered stretch A—B, the direction of traffic, as determined by the signals, cannot be reversed, and, therefore, two trains moving in opposite directions cannot be permitted in the stretch at the same time. As the train leaves the section B—D and enters section D—C, track relay T^s closes, thereby permitting signal relay R' to close, which latter in turn causes signal S' to change to

"clear" indication so that a following westbound train may now enter the stretch A—B. The operation of the apparatus dur-

ing the passage of the westbound train through the remainder of the stretch will be evident from the operation as thus far described.

5 I will assume now that with the signals set as shown in the drawing, an eastbound train approaches the stretch A-B. As this train enters preliminary section G-A, it opens track relay T, thereby causing polarized relays K' and K to be energized through the following circuit—from battery 10 through wire 34, contact 31 of track relay T¹, wire 30, winding of polarized relay K thence through the contacts of track 10 relays T³, T² and T', as hereinbefore traced, then through winding of polarized relay K', wire 33, contact 22 of track relay T, wire 35, and common wire 7 to battery 10. The direction of current in this circuit is such as 15 to cause the armatures 15 and 15^a of the polarized relays to be reversed from the positions in which they are shown in the drawing, thereby causing westbound signals S', S³ and S⁵ to change to danger indication 20 and eastbound signals S², S⁴ and S⁶ to change to clear indication. The operation of the apparatus during the passage of the eastbound train through the stretch is similar to that during the passage of the westbound train hereinbefore described, hence 25 no further explanation is necessary.

As hereinbefore mentioned, the branch circuit for signal relay R' includes contacts 15^a of polarized relay K, and the branch for 30 signal relay R² includes contacts 15^a of polarized relay K'. The purpose of this control of these signal relays is as follows: If by accident the armatures 15 of the two 35 polarized relays should get into non-corresponding positions—for example, if armature 15 of relay K should become reversed and armature 15 of relay K' should remain in the position shown—then the circuits for both relays R' and R² would be opened so 40 that both end signals S' and S² would be at danger and no train could enter the stretch from either direction. Of course, if armature 15 of relay K should remain in the position shown, and the armature 15 of relay 45 K' should become reversed, all of the signal relays would be deenergized and all of the signals would therefore indicate danger.

Referring now to Fig. 2, the system here shown is the same as that shown in Fig. 1, 50 except as to the means for controlling the signals as to direction of traffic, this control being accomplished in Fig. 2 by manually operable circuit controllers P and P' instead of by the track relays of the preliminary sections as in Fig. 1. In Fig. 2, the preliminary sections are omitted and the circuit controllers P and P' are substituted.

The operation of the system shown in Fig. 2 is as follows: As shown in the drawing,

the controllers P and P' are set for a west-bound train to pass through the stretch, the circuit for polarized relays K and K' being from battery 9 through wire 38, circuit controller P, wire 39, winding of relay K', contacts 24, 26 and 28 of track relays T', T² 65 and T³ respectively, winding of relay K, wire 37, circuit controller P', wires 40, 32 and 7 to battery 9. To set the signals for an eastbound train to pass through the stretch requires that both circuit controllers P and P' be reversed by an operator at each end of the stretch. Current then flows from battery 10 through wire 36, circuit controller P', wire 37, thence through the same circuit as before to circuit controller P, then 70 through wires 41, 35 and 7 to battery 10. This current is in such direction as to cause armatures 15 of the polarized relays K and K' to be reversed, thereby causing the westbound signals to change to danger and the eastbound signals to change to clear. It will be noted that when the signals are set for traffic in one direction or the other, reversal of one or the other of the circuit controllers P or P' by an operator at the corresponding end will have no effect on the signals. Reversal of the direction of traffic requires joint action on the part of both operators, and this joint action may be obtained by suitable communication of any 85 form, such as telegraph or telephone (which means for communication is not shown in the drawing).

The features pointed out hereinbefore concerning the impossibility of reversing 90 the signals while a train is in the stretch, and the protection against false operation of the signals due to non-corresponding positions of the polarized relay armatures 15 apply to the system shown in Fig. 2 as well 95 as to that shown in Fig. 1.

Although I have herein shown and described only two forms of railway signaling system embodying my invention, it is understood that various changes and modifications may be made therein within the scope of the appended claims without departing from the spirit and scope of my invention.

Having thus described my invention, what I claim is:

1. In combination, a stretch of single track, signals located at intervals for governing traffic in one direction through the stretch, and other signals located at intervals for governing traffic in the other direction through the stretch, a signal relay for the control of each signal, track circuits for the stretch including track relays; a signal relay circuit including in multiple the signal relays for the signals which govern 120 traffic in one direction, the branch for each signal relay being controlled by a track relay; another signal relay circuit including 125

in multiple the signal relays for the signals governing traffic in the other direction, the branch for each of the latter signal relays being controlled by a track relay; and means for energizing one or the other of said signal relay circuits.

2. In combination, a stretch of single track, signals located at intervals for governing traffic in one direction through the stretch, and other signals located at intervals for governing traffic in the other direction through the stretch, a signal relay for the control of each signal, track circuits for the stretch including track relays; a signal relay circuit including in multiple the signal relays for the signals which govern traffic in one direction, the branch for each signal relay being controlled by a track relay; another signal relay circuit including in multiple the signal relays for the signals governing traffic in the other direction, the branch for each of the latter signal relays being controlled by a track relay; and means controlled by the track relays for energizing one of said signal relay circuits or the other.

3. In combination, a stretch of single track, signals located at intervals for governing traffic in one direction through the stretch, and other signals located at intervals for governing traffic in the other direction through the stretch, a signal relay for the control of each signal, a signal relay circuit for the relays for the signals which govern traffic in one direction, another signal relay circuit for the relays for the signals which govern traffic in the other direction, track circuits for the stretch including track relays for the control of said signal relay circuits, means for energizing each signal relay circuit, a polarized relay for each signal relay circuit for causing the corresponding circuit to be energized or de-energized according as the relay is energized in one direction or the other; a circuit for said polarized relays, the relays being so connected in said circuit that when the circuit is energized in one direction or the other, one or the other of the signal relay circuits is energized; means for energizing said polarized relay circuit in one direction or the other.

4. In combination, a stretch of single track, signals located at intervals for governing traffic in one direction through the stretch and other signals located at intervals for governing traffic in the other direction through the stretch, a signal relay for the control of each signal, a signal relay circuit for the relays for the signals which govern traffic in one direction, another signal relay circuit for the relays for the signals which govern traffic in the other direction, track circuits for the stretch including track relays for the control of said signal relay circuit.

cuits, means for energizing each signal relay circuit, a polarized relay for each signal relay circuit for causing the corresponding circuit to be energized or de-energized according as the relay is energized in one direction or the other; a circuit for said polarized relays, the relays being so connected in said circuit that when the circuit is energized in one direction or the other, one or the other of the signal relay circuits is energized; preliminary track sections one extending from each end of the stretch, and means controlled by a train in one preliminary section or the other for energizing said polarized relay circuit in one direction or the other.

5. In combination, a stretch of single track, signals located at intervals for governing traffic in one direction through the stretch, and other signals located at intervals for governing traffic in the other direction through the stretch, a signal relay for the control of each signal, track circuits for the stretch including track relays; a signal relay circuit including in multiple the signal relays for the signals which govern traffic in one direction, the branch for each signal relay being controlled by a track relay; another signal relay circuit including in multiple the signal relays for the signals governing traffic in the other direction, the branch for each of the latter signal relays being controlled by a track relay; a polarized relay for each signal relay circuit for causing the corresponding circuit to be energized or de-energized according as the polarized relay is energized in one direction or the other; a circuit for said polarized relays, the relays being so connected in the circuit that when the circuit is energized in one direction or the other, one or the other of the signal relay circuits is energized; means for energizing said polarized relay circuit in one direction or the other, and a contact of each polarized relay included in the branch for one of the signal relays which is controlled by the other polarized relay.

6. In combination, a stretch of single track divided into a plurality of sections, a pair of opposing signals located substantially at each junction of adjacent sections for governing traffic in opposite directions, a signal relay for the control of each signal, track circuits for the sections including track relays; a signal relay circuit including in multiple the signal relays for the signals which govern traffic in one direction, the branch for each relay being controlled by a track relay for the section through which the corresponding signal governs traffic; another signal relay circuit including in multiple the signal relays for the signals which govern traffic in the other direction,

the branch for each of the latter relays being controlled by a track relay for the section through which the corresponding signal governs traffic; and means for energizing one or the other of said signal relay circuits.

In testimony whereof I affix my signature in presence of two witnesses.
